ABSTRACT

Means for locating and securing rafters defined by at least two similar units on and relative to columns serving to support an end of the rafter provided with a first location means between the column top and the end of the first of the rafter units and a second location means between the column side and a plate extending laterally of and into the joint between the similar units in which the first and second location means also serve as a means for securing the rafter units to the column.

LOCATION MEANS FOR RAFTER ON COLUMNS

BACKGROUND OF THE INVENTION

This invention relates to location means for or as between rafters or beams for buildings and upright columns for supporting such rafters, which location means may also serve as securing means therebetween.

More particularly this invention relates to the location and to the location and securing of composite rafters or beams.

By the term composite rafters is meant rafters constructed of two or more units which may or may not be identical, which units are jointed or fastened together to form a single rafter or beam of a length determined by the number of such units used in the construction of such a rafter. The term rafter as used herein is to be taken as a reference to a composite rafter.

It is an object of this invention to provide positive means for the location and securing of the distal ends of rafters to the upper ends of columns designed to support such rafters.

PRIOR TECHNIQUES

In the construction of portal-type buildings, columns are erected and rafters are fabricated on or off the site and when on the site are lifted, usually by a crane into approximately the correct position when they are lowered onto the top of the columns for securement thereto. Hitherto, the system has been to lower the rafter onto the top of the columns and align bolt holes in both the tops of the columns and ends of the rafters and slide a bolt through the aligned holes to secure the rafters to the tops of the column.

Such an arrangement has the difficulty that it is necessary for the holes to be aligned and once aligned to maintain alignment while the bolt is slid through the holes. Difficulties can arise in endeavoring to keep the holes aligned for a sufficient length of time for the bolt to be passed through the holes.

It is a further object of this invention to overcome this disadvantage and permit the rafter to be lowered onto the columns and, in the last part of the lowering operation, the location means of this invention acting to position or locate the rafter as it is lowered into juxtaposition with this column.

SUMMARY OF THE INVENTION

According to this invention, there is provided means for locating rafters on and relative to columns adapted to support an end of such a rafter including a first location between the top of the column and the end of the rafter and a second location means between the side of the column and a plate, extending laterally of and into the joint between adjacent units composing said rafter.

Further according to this invention, there is provided means for locating and securing rafters on and to columns adapted to support an end of such a rafter including a first location means between the top of the column and the end of the rafter and a second location means between the side of the column and a plate, extending laterally of and into the joint between adjacent units composing said rafter, the arrangement being such that said first and/or said second location means also serve as means for securing said rafter to said column.

Formed into and projecting from the upper surface of the column may be a lug provided with a hole therein

of a suitable size adapted to receive and accommodate a projection of or a projection from the butt end of said rafter, said projection extending preferably with its axis substantially parallel to the axis of the rafter when the latter is in position, located relative to the column. The height of the hole in the lug and the positioning of the projection of or on the rafter is such that with the rafter resting on top of the column, the projection and hole in the lug may be aligned. The lug may be an upstanding abutment formed integrally with the column or may be a separate integer cast into the column with that portion in which the hole is located extending from the column. The projection may be formed by an extension of a reinforcing tendon or a pin cast into the rafter or a pin rod, shaft, or bolt welded to (or formed integrally with) the reinforcing tendon end plate at the butt end of the rafter. This arrangement forms a suitable first location means between the top of the column and the end of the rafter.

Projecting from and formed or formed integrally with or cast into the column and being substantially parallel to the axis of the rafter (when the latter is in position), may be provided a second projection adapted to be received in a hole provided in a lug formed integrally with a plate secured to said rafter and between adjacent units composing the rafter. The arrangement described in this paragraph forms a suitable second location means between the side of the column and the plate secured between adjacent units of the rafter.

When the projection on the end of the rafter is accommodated within the hole in the lug in the column, similarly the projection from the column is accommodated within the hole in the lug of the plate secured between adjacent units of which the rafter is composed. The second projection, being that projecting from the column, may be in the form of a bolt, a pin or an extension of a reinforcing tendon on the column.

Alternatively, the projections (one extending from the end of the beam and the other from the column) may be disposed with their axes at an oblique angle to the axis of the rafter.

Where the projections are formed from a metal (which, while usefully may be a suitable alloy or aluminum or of bronze is preferably steel), the distal ends thereof may be screw threaded to threadly receive a nut or may be slotted to receive a wedge so as to be capable of securing the end of the rafter to the column. Alternatively, when the rafter is located in position, the two projections may be bonded by a suitable known industrial bonding material or welded to their respective lugs or may be deformed in a rivet-like manner to achieve securement of the rafter to the top of the column.

However, the projections, by their co-operation with their respective lugs may merely serve to locate the rafter in relation to the beam and separate securing means may be used, for example a bolt or bolts passing through aligned holes in the rafter and column or straps passing around both the rafter and top of the column or by way of bolts securing an aligned pair (or pairs) of further lugs, one of each pair disposed on the rafter and column respectively.

However, alternative constructions of either or both the first and second location means may be used to achieve location such as a blind keyway in either the rafter or column adapted to co-operate with a complementary key secured to or formed integrally with, re-

spectively, either the column or rafter. Another operable arrangement would be a three sided abutment or socket located on either or both the rafter or column and adapted to receive a complementary portion, of respectively, the column or rafter.

Further while the above general description of the invention makes reference to only one securement means each between the top of the column and the end of the rafter on the one hand and between the side of column and said lug or plate on the other hand, two or more such securement means may be used at either or both positions should individual circumstances so dictate.

BRIEF DESCRIPTION OF THE DRAWINGS

Many modifications of the above described invention may be made without departing from the spirit or scope thereof and by way of example only and not by way of limitation reference will be made to one form, of the invention with reference to the accompanying drawings in which

FIG. 1 shows a perspective view of a unit for use in forming the rafters and

FIG. 2 shows a side elevation of one aspect of this invention.

DETAILED DESCRIPTION OF THE INVENTION

In the drawings, a column and rafter formed of a plurality of units constructed of a castable material, and of the type described.

The column, generally indicated by arrow 1 is composed of a desired number of standard units 2 (as shown in FIG. 1).

Slightly widened special column sections 3 are placed on column beam unit 2 to which is secured a knee joint generally indicated at 4 and comprising a base section 5 and a laterally extending portion 6.

The rafter, generally indicated at 7, is composed of a series of unit 2 which, with suitable stressing form the rafter 7.

Extending from and cast into the lateral portion 6, towards the base section 5 of the knee joint is a lug unit 8, that portion of which extending from the lateral portion 6 forming the lug itself which is indicated at numeral 9.

Cast into and extending from distal end 10 of the lateral portion 6 at right angles to the lug 9 is a bolt 11.

Secured to end plate 7a of the rafter (to which the ends of the reinforcing tendons of the rafter may be secured) is a bolt 12 whose axis is parallel to the axis of the rafter 2 and whose positioning is such that with the rafter 7 resting on the lateral portion 6, the bolt 12 is aligned so as to be accommodated within a suitable hole provided in the lug 9.

The distance of the lug 9 from the end 10 of the lateral portion 6 is, in this described form of the invention, commensurate with the length of one unit 2 such that a plate 13 may be bonded between the last two units 2 and thus stressed into the rafter, so as to provide a lug

14 extending laterally from the rafter 7. A hole may be provided in lug 14 adapted to have accommodated therewithin the end of the bolt 11.

In the positioning and securing of the rafter 7 to two columns it will be appreciated that the rafter may be formed as an inverted V, each end of which is adapted to be secured to the column of the type shown in FIG. 2.

Thus, the rafter, usually with a supporting cradle is lifted by a crane to a position such that the ends of the rafter are positioned immediately above the lateral portion 6 of the rafters' two supporting columns.

When the rafter is lowered, the bolt 12 is guided so as to pass through the hole in the lug 9 and the lug 14 is guided so as to pass over the bolt 11. Thus, the lowering of the rafter onto its supporting beams is a simple exercise and locates the beam by virtue of the locating of the bolt 12 in the hole of the lug 9 and the bolt 11 in the hole in the lug 14.

To achieve the securement of the rafter to the column nuts may be engaged on the bolts 12 and 11 and tightening same to secure the rafter in its position.

FIG. 2 shows a "Y" form to the top of the column 1 for supporting rafters in the center of a large building.

Where the column 1 is on the outside of the building, integers 2a, 3a, 4a, 5a and 8a will not, of course, be there and the profile of the column will follow the broken line 15.

Thus, by this invention, there is provided an improved means for the securing of rafters of the type described to columns.

I claim:

1. Means for locating and securing a rafter defined by at least two similar units arranged in end to end jointing relationship on and relative to a column for supporting an end of such rafter, with the column having an upper end surface and a distal side surface extending normal to the upper end surface, said means including a first lug projecting from the upper end surface of the column, said first lug having an aperture therein, a first bolt extending from the butt end of the rafter, the axis of the first bolt being substantially parallel to the axis of the rafter, a second bolt projecting from the distal side surface of the column and extending substantially parallel to the axis of the rafter, a second lug secured between the joining ends of the units and extending laterally therefrom, the second lug having an aperture therein, the apertures of the first and second lugs, when the rafter is in position, receiving the first and second bolts, and means cooperable with each of the bolts for securing the rafter to the upper end surface and the distal side surface of the column.

2. The means for locating and securing a rafter as claimed in claim 1 in which the location of the aperture in the first lug and the positioning of the first bolt, the location of the aperture in the second lug and the positioning of the second bolt are such that the bolts and the apertures in the lugs can be aligned.
